UNITED STATES PATENT OFFICE

2,453,572

MEANS FOR VARYING THE TUNING OF
STRINGED INSTRUMENTS

David John Ferrier, St. Kilda, Victoria, Australia

Application December 9, 1947, Serial No. 790,626
In Australia June 12, 1945Section 1, Public Law 690, August 8, 1946
Patent expires June 12, 1965

11 Claims. (Cl. 84—312)

1

This invention relates to means for varying the tuning of steel guitars and other stringed instruments and its objects are to enable the tunings of strings to be varied instantly by semi-tones or other predetermined amounts; to obtain a greater range of open tunings with steel guitars and other similar instruments; to make it easier to get the full range with the said instruments; and to enable a much wider variety of chords and effects to be produced than is possible with existing instruments of this type.

The pitch of each string of a steel guitar or other like stringed instrument is normally adjusted to a particular note, and although it is possible to adjust the pitch of the strings by the usual method, no means are provided for rapidly altering the pitch of a string by varying its tension while the instrument is being played. A purpose of this invention, therefore, is to provide mechanism for enabling this to be done in a simple and efficient manner, whereby the instrument may be employed to obtain a greater number of musical effects.

I attain these objects by the mechanism illustrated in the accompanying drawings, in which—

Figure 1 is a perspective view, partly in section, of a steel guitar embodying mechanism according to this invention.

Figure 2 is a view in elevation of the mechanism shown in Figure 1, and

Figure 3 is a fragmentary view showing an alternative method of attaching the buffer spring.

Referring to the drawings, wherein the same reference numerals are used to indicate like parts, the reference numeral 10 indicates the frame or body of a steel guitar. A recess or cavity 11 is formed in the frame or body 10 and plates 12 are secured to the side walls of said recess.

Bearing plates 13, 14 are arranged in the recess 11 and are secured at their ends to the plates 12. The bearing plate 13 may, if desired, also constitute the bridge for the strings. Rods 15, 16, 17, 18 are longitudinally disposed in the frame and are slidable in holes formed in the bearing plates 13, 14. The ends of the rods 15, 17 are connected by a bar 19 secured to their lower surfaces and the ends of the rods 16, 18 are connected by a bar 20 secured to their upper surfaces. Links 21, 22 are connected to the bars 19, 20 respectively and at their other ends are pivotally attached to levers 23, 24 respectively which extend transversely of the frame and are pivoted at 25 to the frame. The free ends of the levers 23, 24 are placed within easy access of the player and are provided with knobs or the like for manual adjustment. The

2

three positions of the levers are suitably marked on the frame.

A rod 26 extends transversely between and is secured at its ends to the plates 12. Four tensioning members 27 are pivotally mounted on the rod 26, the said members having slots 28 in their upper ends by which the ends of the strings 29 are attached to the members 27. Rollers 30 are attached to the lower ends of the tensioning members 27, and buffer springs 31 connect the said rollers to a rod 32 mounted in the frame 10.

The tension of the buffer springs 31 may be made adjustable by attaching the ends of said springs to hooks 31¹ the threaded shanks of which pass through holes in a rod 32, the required adjustment being effected by nuts 31² (see Figure 3).

A pair of screws 33, 34 is provided in each of the slidable rods 15, 16, 17, 18, the said set screws 33, 34 being adjustable to different heights and being adapted to engage the upper surfaces of the rollers 30 when the levers 23, 24 are operated, thereby pivoting the tensioning members 27 to varying amounts.

The mechanism is adjusted so that when the levers 23, 24 are in the right-hand position as viewed in Figure 1, the rollers 30 are in engagement with the lower surfaces of the rods 15, 16, 17, 18 and the strings are tuned to their lowest pitch. When either of the levers 23, 24 is moved to the central position the corresponding set-screws 33 engage the upper surfaces of the rollers 30 and the corresponding strings are tensioned to a higher pitch.

By moving either of the levers 23, 24 to the left-hand position in Figure 1 the corresponding set screws 34 are brought into engagement with the upper surfaces of the rollers 30, thereby further increasing the tension in the strings. Thus for the three different positions of each lever 23, 24 the tunings of the pair of strings associated therewith are adjusted to three different values. The particular pitch to which each string is altered at each position of the lever may be varied by adjusting the corresponding set-screw 33 or 34.

Although in the instrument described above the strings are adjusted in pairs, it will be understood that the strings may also be controlled individually or in any desired combination, and that each movement of a lever may effect a variation in the pitch of any particular string of a tone, a semi-tone, or any suitable multiple or fraction thereof.

As examples of the effects obtainable it is pointed out that in a steel guitar the open strings are tuned to the chord of A major, namely, A, C sharp, E. This chord can be changed, for example, by

decreasing the tension to form the chords of C major (G, C, E); E major (G sharp, B, E); A minor (A, C, E); E minor (G, B, E), or C sharp minor (G sharp, C sharp, E).

By way of other examples of the effects that may be achieved by changing the tension of the strings by the mechanism of this invention, it may be mentioned that "passing" chords such as "ninth," "sevenths" and "augmented" and "diminished" chords can be obtained by operation of the mechanism.

As will be clear to musicians, there are a number of other possible effects, obtainable by variations of the tuning of the strings in accordance with the invention; thus, for example, any inversions of chords can be obtained.

I claim:

1. Means for varying the tuning of a string in a stringed instrument, comprising a tensioning member pivoted to the frame of the instrument, one end of the string being affixed to the upper end of said member, a roller on the lower end of the tensioning member, a member slidably mounted in the frame, an abutment on the slidable member, and means for actuating the slidable member in order to move the abutment thereon into engagement with the roller on the tensioning member, thereby altering the tension of the string.

2. Means for varying the tuning of a string in a stringed instrument, comprising a tensioning member pivoted to the frame of the instrument, one end of the string being affixed to the upper end of said member, a roller on the lower end of the tensioning member, a rod slidably mounted in the frame, abutments on the rod, and means for actuating the rod in order to move the abutments thereon into successive engagement with the roller on the tensioning member, thereby altering the tension of the string.

3. Means for varying the tuning of a string in a stringed instrument, comprising a tensioning member pivoted to a rod extending transversely of the frame of the instrument, one end of the string being affixed to the upper end of the tensioning member, a roller on the lower end of the tensioning member, a rod disposed longitudinally in the frame and slidably mounted therein, set-screws in the rod at intervals therealong adapted successively to engage the upper surface of the roller as the rod is moved longitudinally, a lever pivoted to the frame of the instrument and movable to a series of positions, and means connecting the lever to the rod so that operation of the lever will move the tensioning member to a series of positions, thereby altering the tension of the string.

4. Means according to claim 3 wherein the tensioning member is movable to any of three positions whereby the tuning of the string may be altered to any of three predetermined values.

5. Means according to claim 3 wherein a buffer spring is provided to compensate in part for the tension of the string.

6. Means according to claim 3 wherein a buffer spring extends between the said roller and an abutment secured to the frame.

7. Means according to claim 3 wherein a buffer spring extends between the said roller and an abutment secured to the frame, means being also provided to adjust the tension of the said buffer spring.

8. Means for varying the tuning of strings in a stringed instrument, comprising tensioning members pivoted to a rod extending transversely of the frame of the instrument, the ends of the strings being affixed to the upper ends of the tensioning members, rollers on the lower ends of the tensioning members, rods disposed longitudinally in the frame and slidably mounted therein, set-screws in the rods at intervals therealong adapted to successively engage the upper surfaces of the rollers as the rods are moved longitudinally, means connecting said rods, a lever pivoted to the frame of the instrument and movable to a series of positions, and means connecting the lever to the rods so that operation of the lever will move the tensioning members to a series of positions, thereby altering the tension of the strings.

9. Means for varying the tension of a string in a stringed instrument, comprising a tensioning member adapted to engage the string and movable to vary the tension of the string, an abutment on the tensioning member, a member slidably mounted on the instrument, and an abutment on the slidable member adapted, on movement of the slidable member, to engage the abutment on the tensioning member, thereby moving the tensioning member and altering the tension of the string.

10. Means for varying the tension of a string in a stringed instrument, comprising a tensioning member adapted to engage the string and movable to vary the tension of the string, an abutment on the tensioning member, a member slidably mounted on the instrument, abutments on the slidable member, and control means connected to the slidable member, the abutments on the slidable member being adapted, on movement of the control means, to successively engage the abutment on the tensioning member, thereby moving the tensioning member and varying the tension of the string.

11. Means for varying the tension of a string in a stringed instrument as claimed in claim 10, and in which the control means is movable to a series of positions, movement of the control means from one of its positions to another effecting a predetermined variation in the tension of the string.
